UNITED STATES PATENT OFFICE.

ALBERT R. MEISTER, OF SACRAMENTO, CALIFORNIA.

DESIGN FOR A MOTOR-VEHICLE BODY.

Application filed May 19, 1925. Serial No. 13,494. Term of patent 3½ years.

To all whom it may concern:

Be it known that I, ALBERT R. MEISTER, a citizen of the United States, residing at Sacramento, in the county of Sacramento and State of California, have invented a new, original, and ornamental Design for Motor-Vehicle Bodies, of which the following is a specification, reference being had to the accompanying drawing, forming part thereof.

Fig. 1 is a top plan view, and Fig. 2 is a side elevation of a motor-vehicle body, showing my new design.

I claim:

The ornamental design for a motor-vehicle body, as shown.

ALBERT R. MEISTER.
